UNITED STATES PATENT OFFICE.

ROBERT B. HAYDEN, OF SEATTLE, WASHINGTON, ASSIGNOR OF ONE-HALF TO GEORGE LLOYD, OF GREAT FALLS, MONTANA.

COIN-ACTUATED CALENDAR BANK.

1,403,601.

Specification of Letters Patent. Patented Jan. 17, 1922.

Application filed July 7, 1920. Serial No. 394,417.

To all whom it may concern:

Be it known that ROBERT B. HAYDEN, a citizen of the United States, and residing at Seattle, in the county of King and State 5 of Washington, has invented certain new and useful Improvements in Coin-Actuated Calendar Banks, of which the following is a specification.

This invention relates to an improvement 10 in banks designed to receive different coins, and to automatically register the deposit of each coin as an addition to the amount already deposited, whereby the bank will indicate the aggregate amount deposited in the 15 coins of the several denominations for which the bank is designed.

An essential object of the present invention is the mounting of the registering elements within the bank structure, so that 20 said elements as a whole may be turned back when desired into a position convenient for manual operation to reset any one or more registers, as may be necessary when the bank is to be emptied.

25 The further object of the invention is to provide simple means whereby the introduction of a particular coin will automatically actuate the register for coins of that denomination, the actuating mechanism being so arranged as to be unaffected when the registering mechanism is turned back for manual adjustment.

In the accompanying drawings:—

Fig. 1 is a bottom plan view of the bank, 35 the cover plate being removed.

Fig. 2 is a similar view with the registering mechanism turned back into a position for convenient manual operation.

Fig. 3 is a longitudinal section on line 40 3—3 of Fig. 1.

Fig. 4 is a transverse section on line 4—4 of Fig. 3.

Fig. 5 is a bottom plan view of a carrying 45 frame and parts carried thereby.

In the accompanying drawings the improved bank is shown as comprising a casing having the bottom thereof formed as a removable cover, to be more specifically described hereinafter. The casing comprises a top wall 1, side walls 2, and end walls 3, the top wall being formed with a transverse slot 4, through which the amounts of the register are visible, and coin slots 5, 6, and 7, here shown as designed to receive coins of different denominations, with the slots, which extend lengthwise the top, corresponding in length to the diameter of the particular coin for which they are designed.

The operating mechanism is mounted 60 upon what may be termed a carrying frame 8 comprising a strip of substantially the interior width of the casing and formed at one end to present a substantially horizontal ledge 9, adapted when the frame is in 65 position to overlie lugs 10 on the side walls of the casing, an upstanding wall 11, the horizontal shelf 12, adapted when the frame is in position to directly underlie the slots 5, 6, and 7 in spaced relation to the top of 70 the casing, a depending wall 13 of slightly less length than the wall 11, and a table 14 having hinged connection with the lower edge of the wall 13. When in place the carrying frame has an aggregate length 75 snugly fitting the interior length of the casing, the table being obviously movable with relation to the rest of the frame on its hinged connection.

The registering mechanism is carried entirely by the table and comprises side plates 80 15 fixed to the table and supporting transverse shafts 16 and 17. On the shaft 16 is mounted a plurality of supply rolls 18, 19, and 20, on each of which is wound a tape 21 85 bearing numbers in multiples of the coin which said tape is designed to register, as is usual. Feed rolls 22, 23 and 24 are mounted on the shaft 17 to align with the rolls 18, 19 and 20, and the respective tapes 21 are 90 wound on said feed rolls, so that as the feed rolls are actuated, the particular tape will be drawn from the supply roll in accordance with the coin deposited. The tapes intermediate the supply and feed rolls pass 95 over a guide bar 25 carried in the side plates 15, which guide bar, when the parts are in position directly underlies the slot 4 of the casing, and thereby permits that portion of the tape or tapes which is directly above 100 said guide bar to be visible, and therefore readable through the slot 4. Beyond the guide bar, the tape passes over idler rolls 26 mounted on the shaft 27 supported in the plates 15, to guide the tapes to and around 105 the feed rolls. Each supply roll is provided with a relatively fixed edge roughened disk 28 which projects beyond the surface of the roll, providing a means for manually adjusting the tape on such roll when the table 110

is turned back as will later appear. Spring fingers 29 are secured to the table and bear on the respective tapes to prevent overrunning of the same. The side plates 15 are 5 provided with projections 30 whereby to accurately position the table and parts carried thereby, when such table is turned down into operative position.

The horizontal shelf 12 of the carrying 10 frame is formed with coin slots 31 corresponding to and registering with the coin slots 5, 6, and 7, in the top of the casing when the parts are in position, guide walls 32 being carried by extensions of the shelf 15 12 to guide the coin following its introduction into the coin slots. The shelf 12 is formed on one side of each coin slot 31 with a guideway 33, and in each of said guideways is slidably mounted an actuator 34. 20 The actuators are held against displacement in the guideways by strips 35 overlying the slots and forming bridge walls for the ends of the slots to hold the actuators in place. The actuators 34 each comprise thin metallic strips having at one end a downwardly inclined lip 36 adapted when the actuator has been moved forwardly a predetermined distance to engage a tooth in a ratchet 37 fixed to the particular feed roll, the operative 25 movement of the actuator serving through this engagement to advance the feed roll a sufficient distance to move the tape connected therewith for a fresh registry through the slot 4. The actuators are 30 formed on the edge next the particular slot 31 with a lateral projection 38 presenting a shoulder 39 which normally bridges or crosses the slot. Therefore on the introduction of the particular coin, this shoulder 39 35 is engaged by the coin, and on forcing the coin through the slot, the actuator is moved to operate the feed roll as described. The actuators are normally held or withdrawn in 40 inoperative position by spring strips 40 secured on the upper side of the ledge 9 and engaging in openings in the ends of the actuator, the lip 36 of each actuator being laterally extended to present a shoulder 41 to limit the inoperative movement of the 45 actuator to such position as will arrange the coin engaged shoulder 39 of the actuator in proper relation to the particular coin slot.

The bottom of the casing 42 which serves as a removable cover is held in place by pins 50 43 on the casing engaging slots 44 in the bottom, a key controlled lock 45 securing the cover in place.

With the parts in position indicated in Fig. 1, it will be apparent that if for any 55 reason, as in removing the coins from the bank, it is desirable to reset the registering mechanism, the table 14 may be turned toward the bottom of the casing on its hinged connection, such table and registering means 60 then assuming the position shown in Fig. 2.

The registering mechanism is then readily accessible from the bottom of the casing and the disks 28 may be readily operated to adjust the registering tapes as desired. The table is provided with a depending projection 46 which may serve as a handle in turning the table to and from an accessible position, this projection being designed to be engaged by the lock 45 on the cover to hold the table in registering mechanism in operative position.

What I claim is:—

1. A coin bank comprising a casing having registering mechanism, coin slots formed in said casing, means operated in the passage 80 of a coin through said slots for actuating the registering mechanism, and means for bodily supporting the registering mechanism to permit said mechanism as a whole to be turned from an operative to an inoperative 85 position for manually adjusting the same.

2. A coin bank comprising a casing formed with coin slots, a carrying frame arranged within said casing, registering mechanism carried by said table, and actuators carried 90 by the frame and adapted to operate said mechanism, said actuators being moved by the coins introduced through said coin slots.

3. A coin bank comprising a casing having a coin slot and an indicating slot, a carrying frame removably arranged in the casing and having a slot to register with the coin slot, an actuator arranged adjacent said frame slot and having a shoulder to be engaged by a coin to move the actuator in one direction, 100 registering mechanism to be operated in the movement of the actuator under the coin, and means for supporting said registering mechanism to permit the same to be turned back into an inoperative position with respect to the actuator and for exposure to 105 permit manual adjustment.

4. A coin bank comprising a casing formed with a coin slot and with an indicating slot, a carrying frame arranged in the casing 110 and having a shelf to underlie that portion of the casing formed with the coin slot, a slot in said underlying portion of the frame to register with the coin slot, an actuator movable in said underlying portion of the 115 frame and adapted to be operated in one direction by the passage of a coin through said registering slot, and a movable shelf forming a part of the carrying frame, and registering mechanism carried by said shelf, 120 said mechanism in one position of the shelf being arranged for cooperation with the actuator and with the indicating slot and in another position of the shelf being accessible for manual adjustment.

5. A coin bank comprising a casing having coin slots and an indicating slot formed therein, a carrying frame arranged within the casing formed with slots registering with the coin slots, actuators carried by said 130

frame operated by the introduction of coins into said coin slots, a table forming part of the carrying frame and having hinged connection therewith, a registering mechanism mounted on the table for registering cooperation with the indicating slot in the casing in one position of the table and adapted to be operated by the actuators in said position, the casing having a removable 10 cover for the bottom thereof, means for locking the cover to the bottom, said means also locking the table to hold the registering mechanism in registering position, and said table being adapted in another position thereof to project the registering mechanism 15 below the bottom of the casing for manual adjustment.

In testimony whereof I affix my signature in the presence of two witnesses.

ROBERT B. HAYDEN.
